MERCANDISE STAND

William Bedingfield, New Richmond, Ohio

Application July 20, 1949, Serial No. 105,709

1 Claim. (Cl. 248—199)

1

My invention has to do with a merchandise stand suitable for clamping engagement to the top of a cash register, counter or other support. The stand is designed primarily for cartons of cigarettes, although it should be understood from the outset that the device may be used for numerous other purposes.

The primary object of my invention is to provide a stand which will place the merchandise in a readily accessible position, so that a cashier in a restaurant, bar or the like need not leave the cash register to obtain the merchandise. Items such as cigarettes and chewing gum, for example, are frequently requested by customers when leaving a restaurant, where the price of the item may be taken from the change received from the dinner check. In restaurants it is customary to keep cigarettes and chewing gum either in a counter upon which the cash register is located, or else keep them in a wall cabinet back of the cashier's station. With either of these arrangements, however, it is necessary for the cashier to leave his station to obtain the pack of cigarettes or the chewing gum, and this not only consumes time but also leaves the cash register unattended. While the time consumed in obtaining each item may be small and only amounts to a few seconds, when multiplied by the number of packs of cigarettes purchased each day or over a period of days, the time mounts up into many minutes and even hours. By means of my invention the merchandise is placed where it may be easily reached by the cashier without stooping or turning away from the cash register. This is of great convenience particularly during rush hours.

It is a further object of my invention to provide a stand which may be easily attached to the top of any cash register regardless of its size, or to other supports of varying dimensions, the attachment being accomplished by means of a clamping leg and cooperating gripping members.

Still a further object of my invention is to provide a merchandise stand having a clamping leg to which spring means are connected whereby the stand may be placed in clamping engagement with a support.

It is a further object of my invention to provide means whereby the merchandise stand may be positioned on any flat surface should it be desired to use the stand other than in clamping engagement with a support.

These and other objects of my invention which will be set forth hereinafter or which will become apparent upon reading these specifications, I accomplish by that construction and arrangement

2

of parts of which I shall now describe certain exemplary embodiments.

Reference is made to the accompanying drawings wherein:

5 Figure 1 is a front elevational view of a preferred form of my invention.

Figure 2 is a side elevational view taken along the line 2—2 of Figure 1.

Figure 3 is a close-up view showing one of the adjustable gripping members by which the front or body portion of the stand is maintained.

Figure 4 is an elevational view showing the stand as it would be attached to the top of a cash register.

15 Figure 5 is a perspective view of a spacer bar for use when the display stand is to be placed on a flat surface.

Figure 6 is a partial front elevational view of a modified form of my invention.

20 Figure 7 is a side elevational view taken along the line 7—7 of Figure 6.

Figure 8 is a partial front elevation of still another modification of my invention.

Figure 9 is a side elevation taken along the line 9—9 of Figure 8.

Briefly, in the practice of my invention I provide a body portion for the retention of the merchandise. The body portion may take the form of a frame comprising a plurality of rods or tubular members arranged to support the merchandise or, alternatively, it may take the form of a sheet metal tray. If desired, the frame or tray may be provided with a plurality of spaced members to divide the body into a number of individual compartments. Connected to the body of the stand at a point intermediate its ends is a clamping leg carrying near its free end a short angularly related foot which, with the portion of the leg lying below the foot, forms a gripping member.

30 The lower part of the body of the stand is provided with one or more gripping members having angularly related parts which cooperate with the clamping leg to clamp the stand to a support, which may be the top of a cash register. In order to secure the desired clamping action, a spring member is provided to draw the leg toward the body of the stand. The stand is attached to a cash register by engaging the angularly related parts of the gripping members attached to the body of the stand to an edge of the cash register whereupon the leg is extended against the tension of the spring member until it can be engaged with an opposite edge of the cash register. If it is desired to use the stand

40 45 50 on a flat surface, a spacer bar is provided to hold

the leg in substantially extended position thus providing the frame with a solid foundation.

Referring now to Figures 1 and 2 of the drawings, the body portion of the stand comprises the spaced vertical members 1 and 2 joined at their bottoms by the horizontal base member 3. Extending rearwardly from the tops of the vertical members 1 and 2 are the short, rearwardly extending members 4 and 5, the ends of which are connected by an upper horizontal member 6. Near the lowermost ends of the vertical members 1 and 2 are placed a complementary pair of short rearwardly extending members 7 and 8 connected at their outermost ends by the lower horizontal member 9. By means of the upper horizontal member 6, the lower horizontal member 9 and the base member 3, a plurality of cigarette cartons 10 may be placed upright on the stand with their lower ends resting on the base member 3 and their rear walls supported by the horizontal members 6 and 9.

The members just described may be formed separately and welded or otherwise joined together as a frame or they may be bent from a single length of stock and suitably welded at the point where the ends of the stock meet. The stock may be either hollow tubing or solid wire. The diameter of the tubing or wire will of course vary with the strength characteristics desired to be imparted to the finished structure, and neither the nature of the material nor its size are intended to be limitations upon my invention.

The size of the frame itself may vary widely and will be governed by the use to which it is to be put. If desired, however, the size of the frame may be made adjustable by forming each of the members in two parts with one of the parts telescoping within the other, as will be readily understood by one skilled in the art.

The frame just described is supported by means of a clamping leg 11 pivotally connected at 12 to the bracket 13 which is welded or otherwise secured centrally of the upper horizontal member 6. Near the bottom of the leg 11 a foot or extension 14 extends inwardly a short distance, and as will be seen more clearly herein-after serves to engage the top edge of the cash register or other support. The foot 14 may be provided with a sleeve 15 of rubber or other suitable material to provide a positive gripping surface and also to prevent scratching of the surface contacted by the foot. The leg 11 may be provided with a crutch tip 16 for the same purposes.

A pair of adjustable gripping members 17 and 18 are slidably connected to the lower horizontal member 9. These gripping members coact with the leg 11 to clamp the stand to the support. The clamping action is obtained by means of the helical spring 19 connected between the leg 11 and a bracket 20 extending upwardly from the lower horizontal member 9. While I have illustrated a tension spring, it will be understood that other spring means could be employed, as for example a torsional spring connected to the upper end of the leg 11 and the bracket 13.

In Figure 3, I have shown in detail the construction of the adjustable gripping members, which may be either the member 17 or the member 18. The gripping members are preferably formed from a strip of sheet metal bent to provide a base portion 21 and angularly related parts 22 and 23, the latter portions being connected by the loop 24 passing around the horizontal member 9. The loop 24 loosely engages

the horizontal member 9 and permits the gripping member to slide along the member 9. The under side of the base portion 21 and the angularly related parts 22 and 23 may be covered with a strip 25 of rubber or other cushioning material. The free end of the base portion 21 is curved upwardly as at 26 for snap engagement with the base member 3. The curved portion 26 terminates in an outwardly extending flange 27 which facilitates adjustment of the gripping member. When it is desired to adjust the position of the gripping member relative to the horizontal bar 9, the flange 27 is pushed downwardly thereby disconnecting the curved portion 26 from the horizontal rod 3 and permitting the gripping member to be moved axially of the horizontal member 9. The gripping member is shown in disengaged position in dotted lines in Figure 3. By sliding the gripping members axially along the horizontal member 9, their position relative to the object to which they are to be attached may be adjusted to the most advantageous point. The adjustable feature is particularly useful in cases wherein the support to which the stand is to be attached is curved through at least a part of its length.

In Figure 4 the stand is shown attached to the top of a cash register. It will be noted that the angularly related parts 22 and 23 of the gripping member 18 engage one edge of the cash register while the lower end of the leg 11 and the foot 14 engage the opposite edge. The tension spring 19 serves to clamp the members firmly in place on the register.

35 A detachable spacer bar 28 slotted as at 29 and 30 (see Figure 5) may be provided if it is desired to use the stand on a flat surface. The spacer bar extends between the bracket 20 and the leg 11 with the slot 29 engaging the bracket 20 and the slot 30 engaging the leg 11, substantially as shown in Figure 2. When in this condition the stand will rest on the base portions 21 of the gripping members and the free end of the leg 11. The cushioning material 25 and the crutch tip 16 will prevent the stand from sliding. It will be apparent that the spacer bar 28 may be removed when the device is to be clamped on the top of the cash register in the manner indicated in Figure 4.

50 In Figures 6 and 7 I have shown a modification of my invention. For simplicity in describing this modification, parts corresponding to the parts already described in connection with Figures 1 to 5 are given like reference numerals. The modification shown in Figures 6 and 7 comprises the use of fixed gripping members in place of the adjustable gripping members 17 and 18. The fixed gripping members are formed by providing a plurality of angularly related pairs of extensions 31 and 32 extending downwardly and outwardly respectively along the horizontal member 9, substantially as shown in the drawings. The extensions may be covered with the sleeves 33 and 34 of rubber or other cushioning material. The extensions 31 and 32 will grip the register in substantially the same fashion as the adjustable gripping members 17 and 18, but, of course, they can not be adjusted. However, it will be noted that when the stand is used on a flat surface, the extensions will not reach the flat surface, and the stand will rest on the lower horizontal member 3 which may be cushioned if desired. Furthermore, it will be noted in Figure 7 that the tension spring 19 is connected directly to the horizontal member 9, the bracket 20 having been

eliminated. With this arrangement it is necessary to twist the spacer bar 28a so that one end is at substantially a right angle to the other. This permits the slot at one end to engage the horizontal member 9 while the slot at the other end engages the leg 11 which is substantially vertical.

If desired, the body of the stand may be divided into a plurality of compartments by means of the spaced dividing members 35, as shown in Figures 6 and 7. The dividing members illustrated are formed from tubing or wire and may or may not be of the same diameter as the frame members. The lower ends of the members 35 are welded or otherwise attached to the base member 3 and the upper ends are bent rearwardly as at 36 (see Figure 7) and attached to the upper horizontal member 6. The dividing members may alternatively take the form of channel bars arranged in opposed relation to provide trackways in which the merchandise may be placed or they may be formed from sheet stock and the like.

Still another modification of my invention is illustrated in Figures 8 and 9, wherein a sheet metal tray has been substituted for the frame of the preceding embodiments. The sheet metal tray comprises a rear wall 37, side walls 38 and a bottom wall 39. The bracket 13 for the leg 11 may be attached directly to the rear wall 37. In this embodiment the gripping member for the body or tray comprises an angle bar 40 extending longitudinally of the tray and provided with a pad 41. A pad 42 may be provided on the under side of the bottom wall 39, if desired.

A panel 43 extending across the tray at its bottom may be provided to retain the packages 35 within the tray. This panel also affords a convenient member upon which to place advertising indicia. In addition to the panel 43, the tray may be provided with a plurality of dividing members, as will be understood. The mode of attachment of the tray-like structure will be identical with that of the preceding embodiments, as is apparent from the drawings.

I have described my invention in several exemplary embodiments in which the stands are attached to the top of a cash register; but it is with the spirit of my invention to attach the stands to other supporting structures, as for example the top of show cases, counters and the like. While the exemplary embodiments are indicative of a large field of utility for my invention, they do not by any means exhaust its utility, and devices responding to my invention are useful in many other fields.

Other modifications may be made in my invention without departing from the spirit of it. Having thus described my invention, what I claim as new and desire to secure by Letters Patent is:

In a merchandise stand for upright attachment to a support, a wire frame comprising a pair of spaced vertical members connected together at their bottoms by a horizontal base member, an upper horizontal member rearwardly disposed with respect to said vertical members and connected to the upper ends of said vertical members, and a lower horizontal member rearwardly displaced with respect to said vertical members and connected to said vertical members intermediate their ends, a supporting leg pivotally connected to said upper horizontal member, said supporting leg carrying near its free end a short angularly related foot, said foot and the portion of the leg extending therebelow forming a gripping element, gripping members slidably connected to said lower horizontal member, said gripping members each having an angularly related portion for gripping engagement with an edge of the support and a flat bottom portion extending forwardly for contact with said base member, said flat bottom portion terminating in a curved portion for snap engagement with said base member.
